UNITED STATES PATENT OFFICE.

HENRY W. FRENCH, OF WATERBURY, CONNECTICUT, ASSIGNOR TO THE LANE MANUFACTURING COMPANY, OF SAME PLACE.

APPARATUS FOR MANUFACTURING COVERED BUTTONS.

SPECIFICATION forming part of Letters Patent No. 323,803, dated August 4, 1885.

Application filed June 30, 1884. (No model.)

To all whom it may concern:

Be it known that I, HENRY W. FRENCH, of Waterbury, in the county of New Haven and State of Connecticut, have invented new ⁵ improvements in Apparatus for Manufacturing Covered Buttons; and I do hereby declare the following, when taken in connection with accompanying drawings, and the letters of reference marked thereon, to be a full, clear, ¹⁰ and exact description of the same, and which said drawings constitute part of this specification, and represent, in—

Figure 1, a central section of the button complete; Fig. 2, the parts set together ¹⁵ preparatory to closing; Fig. 3, a perspective sectional view of the four parts of the button detached; Fig. 4, a vertical section of the closing mechanism in its normal position with the parts of the button introduced; Fig. 5, a ²⁰ section of the same, showing the mechanism as having closed the parts together.

This invention relates to an improvement in the manufacture of that class of buttons which are composed of a metal back, an open ²⁵ metal front with filling of a character to present an ornamental appearance through the open front, the back and front closed together to complete the button. These buttons of the simplest character are composed of four parts: ³⁰ first, the front A; second, the back B; third, the ornamental disk C, and, fourth, the filling D.

The front A is struck up in cup shape from sheet metal, with its face more or less open, ³⁵ so that the material beneath it may be exposed through the openings. The back B is of similar cup shape, but of less extreme diameter than the front, and so that its edge will pass within the flange of the front. In the center ⁴⁰ of the back is a depression or other device to form the eye.

In the usual method of putting these parts together the operator takes the part B in one hand; then introduces into that part first the ⁴⁵ filling-piece D, which is made from pasteboard, felt, or any suitable material; then upon that the part C, and, finally, the cap or front A is set over all, as seen in Fig. 2. Then the parts so set together by hand are ⁵⁰ introduced into a die, which will close the edge of the cap or front around the edge of the

back, as seen in Fig. 1. As before stated, this is the simplest of this class of buttons. In other styles a greater number of pieces are employed—that is, in some cases the face is ⁵⁵ ornamented by different colors or material through circles of openings in the front. In that case the material for ornamentation is cut in rings, which will be exposed through their respective open portions of the front. This ⁶⁰ setting together of the parts by hand preparatory to their introduction into the die consumes so much time as to make this class of buttons expensive. Great care is necessarily exercised in the proper placing of the parts ⁶⁵ together, and each part introduced must be held by the finger until the next is in place, and, finally, all the parts must be held within the fingers until located in the die, and it frequently occurs that in introducing the parts ⁷⁰ so assembled into the die they will be displaced and make a defective button. Such misplacing of the parts causes a very considerable loss to the manufacturer.

The object of my invention is to simplify ⁷⁵ this method of manufacture and avoid the hand assembling; and it consists in the apparatus, as hereinafter fully described, and particularly recited in the claim.

I will first describe an apparatus by which ⁸⁰ my method of manufacture may be carried out.

E represents the follower, which ^{ce} fast in the reciprocating slide of a button-closing press, it being constructed with a ⁸⁵ shank, F, for convenience of attachment to the slide. Upon this follower is an annular sleeve, G, the diameter of the follower and the internal diameter of the sleeve corresponding substantially to the front or cap of the button. ⁹⁰ The collar is held upon the follower by a spring, H, which holds the follower in a position with its open mouth considerably below the lower end of the follower, but yet so as to permit the follower to pass down through ⁹⁵ the collar when the collar is held for such movement.

On the bed of the machine, in axial line with the follower E, is a stationary stud, I, fixed in the base J. Around this stud I is a sleeve, K, ¹⁰⁰ between which and the base is a spring, L, and so that the sleeve K rests upon the top of

the spring, the spring itself resting on the base J, and so that pressure applied to the upper end of the sleeve K will force the said sleeve toward the base, and the reaction of the spring return the sleeve when the power which depressed the sleeve is removed.

a is a tubular die constructed to set upon the sleeve K and be concentrically located thereon. This may be done by a flange on the one to set into a recess on the other, as shown. The upper end of this die has a recess forming a shoulder, b, corresponding to the lower end, d, of the sleeve G. The stud I locates the die a in axial line with the follower E and the sleeve G, which it carries, and so that as the slide of the press descends the lower end, d, of the sleeve G will enter the recess in the die a and strike upon the shoulder b. Within the die a is a follower, e. This follower is free for vertical movement within the die a—that is to say, is loose therein—and is prevented from escaping from the die by a pin, f, through the wall of the die into a vertical groove in the side of the follower e. The internal diameter of the die corresponds substantially to the diameter of the back of the button, and the upper face of the follower e corresponds to the under or rear face of the back, and has centrally through it an opening, g, which will permit the eye portion of the back to set below the face of the follower.

The front or cap of the button, it will be understood, as before described, is of larger diameter than the back; hence the internal diameter of the sleeve G is slightly greater than the internal diameter of the die a; but the upper end of the opening in the die a is countersunk or made flaring, as at h, the extreme diameter corresponding to the extreme diameter of the front or cap.

The operator first takes the front A of the button and introduces it into the mouth of the sleeve G, as seen in Fig. 4, the internal diameter of the sleeve G being such with relation to the front or cap A that the cap is readily held within the sleeve by frictional contact only; then taking the die a from its seat in the sleeve K and holding it in one hand with the other, first throws the back into the cavity in the die, which readily locates itself upon the face of the follower e; then places the disk-like filling C into the same opening in the die, which readily locates itself within the back of the button, and then the ornamenting-disk D is thrown in like manner into the die upon the filling, each finding its own proper position in the die, and without any effort on the part of the operator. These parts of the button thus introduced, the

die is reset upon the sleeve K. Then the follower E, with its sleeve G, carrying the front A, is forced down, as seen in Fig. 5, the end d of the die first striking the shoulder b, and there coming to a bearing. The spring H above the sleeve G yields, as also the spring L below the sleeve K, and until the follower e comes to a bearing upon the stud I; then the follower e, standing and supporting the back with its contents, the follower E continues its descent with the cap until the lower end of the sleeve K comes to a bearing upon the base, as also seen in Fig. 5, which arrests the farther downward movement of the die a, and just as the flaring portion h has arrived at a position around the back; then the follower E, still continuing, forces the face A still farther downward. The flange of the face or cap entering this flaring portion h in the die a is contracted around the outer edge of the back and closed together, as seen in Fig. 5, and as also seen in Fig. 1, which completes the button.

By employing the removable die a, with its loose follower e, so as to form a cavity to receive the back and all parts to form the button, except the cap or front, the parts to form the button are assembled without any special care or attention on the part of the operator. As no misplacement of those parts is possible, each, guided by the walls of the die, must find its own proper location, the loss in consequence of defective buttons is avoided, cheaper and less experienced help may be employed in the manufacture of this class of buttons, and the cost of manufacture also greatly reduced.

The description of the operation as applied to the making of a four-part button will be sufficient to enable those skilled in the art to employ the invention in the manufacture of buttons of this class composed of more or less parts.

I claim—

In a machine for making buttons, the combination of a stud, I, sleeve K, supported upon a spring around said stud, the follower E, sleeve G, and spring H, surrounding said follower, concentric with and arranged to move in line with said stud I, the removable die a, with its follower e, said die and follower e constructed to receive the back and filling parts of the button, and the sleeve G, to receive the cap or front, substantially as described.
